GRATE STRUCTURE

Harry S. Lee, Detroit, Mich.

Application May 22, 1931, Serial No. 539,369

8 Claims. (Cl. 126—167)

My invention relates to supporting grates and has particular reference to a grate structure for supporting material being passed through a combustion chamber.

5 While the invention may be utilized for various purposes as a supporting grate, I particularly contemplate its use as a support for red hot cement clinker immediately after its ejection from the burning kiln. As described in some detail in my 10 copending application, Serial No. 420,326, filed January 13, 1930, it has been found that cement clinker is vastly improved by subjecting it to an air draft immediately after it leaves the burning kiln. One manner of subjecting the hot clinker to an air draft at this period is to let it fall directly from the kiln upon a support over which it is moved by sometype of travelling stoker and directing an air draft up from below the said support through the bed of clinker which has been 15 deposited upon the said support as it is moved thereacross.

An object of my invention is to prevent any possible clogging of the passages through the support by means of which the air is directed upwardly through the clinker bed whereby the efficiency 20 of this secondary combustion operation might be impaired.

Another object of the invention is to provide a supporting grate structure which, while affording 25 a substantially continuous supporting surface across the top thereof, includes means for directing the air draft from below in a forwardly direction corresponding to that in which the hot clinker is being actuated. This arrangement, 30 wherein the air is directed through the clinker at an angle between the horizontal and vertical, permits the air to contact a maximum amount of clinker during its upward passage therethrough and at the same time assists in pushing the clinker 35 forwardly along its support.

40 A further object of the invention is to eliminate to some extent the terrific cutting action of the highly abrasive cement clinker as it is actuated along the support. By so arranging the supporting grate bars that air passages are provided therethrough over a relatively large portion of its upper surface, what may be regarded as a partial air cushion support is provided which relieves the top surface of the supporting grate somewhat 45 from the deleterious effect of the abrasive passing thereover.

50 Other objects and meritorious features will be found in the particular combination and arrangement of parts whereby replacement of the various units comprising the supporting surface as a

whole may be easily accomplished without interfering with other units, as well as in the simplicity of design which insures cheapness of construction and ease in assembly.

5 Referring now to the drawing, like numerals refer to like parts throughout the several figures and

Fig. 1 is a transverse section through a portion of the supporting surface, and

Fig. 2 is an end elevation.

10 A plurality of supports 10, here illustrated as I-beams of conventional type, are arranged in substantially parallel relation at spaced apart intervals along the path over which the clinker is to be conveyed. The supporting surface, over 15 which the clinker 11 is drawn by some type of chain stoker, is composed of a plurality of supporting grate bar assembly units designated by the numeral 12.

Each unit 12 comprises a plurality of parallel 20 grates bars 14 intermediate the extremities of the unit and a plurality of very similar—yet somewhat differently shaped—bars 16 at each end thereof.

All of the bars are of the same general form 25 and include lower portions and upper portions which cooperate when the bars are positioned as illustrated to form a plurality of tortuous passages 18 which direct an air draft vertically upward through the supporting grate surface and 30 subsequently shift its direction of flow to an angle directed forwardly, as at 20, intermediate the vertical and horizontal. It is to be noted that the lower portions 22 of the intermediate grate bars 14 depend substantially further across their span 35 than the end bars 16 and that the lower extremities of all of the bars are rounded as at 24 while the upper extremities thereof are flat as at 26 to form a supporting surface for the clinker. 40 The rounded extremity 24 of the depending portions cuts down the resistance to the air draft passing upwardly through the tortuous passages 18 and it will be noted that the opening at the upper extremity of the passage is of substantially less area than that at the lower extremity. The 45 rate of change in the cross sectional area between each bar is substantially uniform. Any material which is small enough to drop through the space in the upper supporting surface of the assembly will necessarily drop completely through the grate 50 bars for this reason. Furthermore, the restriction of the air passages at their upper extremities will tend somewhat to increase the velocity of the air passing therethrough.

The extremities of each bar are provided with 55

- widened flange portions 28 which are adapted to abut one another to maintain the bars properly spaced. Each bar is likewise provided with a projecting portion 30 intermediate its extremities. 5 These are likewise adapted to abut to insure the proper spacing across the entire span of the grate bar assembly.

The lower portions 22 of all the bars are apertured at spaced points to receive the positioning 10 tie rods 32 and 34. These rods are offset at their extremities, as indicated at 36, and adapted to abut one another to maintain the same spacing between the grate bar units as the flanges 28 maintain for each individual bar.

- 15 The end bars, the lower portions of which are somewhat shorter than the intermediate bar, are adapted to rest upon the supporting surface provided by the I-beams 10 and the extreme intermediate bar 14 of each grate bar assembly 20 unit is adapted to abut the extremity of the flange 38 of the said I-beam to position the assembly unit with respect thereto.

While I have illustrated my improved grate structure as a fixedly positioned assembly supporting material which is pushed thereover by a chain stoker, it will be apparent that the same structure may constitute a travelling grate stoker if desired, the advantages of the grate being inherent in the bar assembly.

- 30 Having described a preferred form of my invention, various modifications thereof will be apparent to those skilled in the art and for that reason I intend to limit myself only within the scope of the appended claims.

35 What I claim is:

1. A grate bar assembly comprising a plurality of grate bars arranged in parallel relation, supporting bars extending transversely of said grate bars, means on each grate bar for spacing adjacent grate bars, said supporting bars cooperating with the spacing means on said grate bars to maintain said grate bars in position, supporting members for the grate assembly, said grate bars having portions depending below said supporting 40 bars, the grate bars adjacent an end of said supporting bar having their depending portion shorter than the other bars of said plurality of grate bars and being positioned upon one of said supporting members for the grate bar assembly.

- 50 2. A grate bar assembly comprising a plurality of grate bars arranged in parallel relation, supporting bars extending transversely of said grate bars, means on each grate bar for spacing adjacent grate bars, said supporting bars cooperating with the spacing means on said grate bars to maintain said grate bars in position, supporting members for the grate assembly, said grate bars having portions depending below said supporting bars, the grate bars adjacent an end of said supporting bar having their depending portion shorter than the other bars of said plurality of grate bars and being positioned upon one of said supporting members for the grate bar assembly, the depending portions of certain of the other bars 60 extending below the top of said supporting member and being positioned adjacent thereto to maintain said assembly in position.

- 70 3. A grate bar assembly comprising a plurality of grate bars arranged in parallel relation, supporting bars extending transversely of said grate bars, means on each grate bar for spacing adjacent grate bars, said supporting bars cooperating with the spacing means on said grate bars to maintain said grate bars in position, supporting members for the grate assembly, said grate bars

having portions depending below said supporting bars, the grate bars adjacent an end of said supporting bar having their depending portion shorter than the other bars of said plurality of grate bars and being positioned upon one of said supporting members for the grate bar assembly, the depending portions positioned upon said supporting member being partially cut away to provide air passageways. 5

4. A grate structure comprising a plurality of 10 grate bar assemblies each comprising a plurality of grate bars arranged in spaced parallel relation, said grate bars having lower portions extending perpendicularly to the plane of the upper surfaces and upper portions extending angularly 15 to said plane and to the lower portions, each grate bar being of decreasing thickness from top to bottom providing tapered passageways therebetween, means on each grate bar for spacing adjacent grate bars, grate bar supporting members extending through the lower portions of said grate bars transversely thereof and cooperating with the spacing means on said grate bars to hold said grate bars in position in said assemblies, the ends of said supporting members of one assembly being positioned adjacent the ends of said supporting members of another assembly to maintain the assemblies in position and to maintain the end grate bars of adjacent assemblies 20 in spaced relation, and means to support said assemblies comprising a beam engaging the bottom of certain grate bars adjacent the ends of the grate bar supporting members. 30

5. A grate structure comprising spaced apart 35 supporting beams, a plurality of grate bar assemblies carried by said beams, each assembly comprising a plurality of parallel spaced grate bars, means on each grate bar for spacing adjacent grate bars, supporting bars extending transversely through said grate bars and cooperating with said spacing means to hold the grate bars in spaced apart relationship, said supporting bars being of a length to extend from the intermediate portion of one beam to the intermediate portion of the adjacent beam, the grate bars at the end of the supporting bars resting upon the beam and being of less depth than the grate bars between the beams. 40

6. A grate structure comprising spaced apart 50 supporting beams, a plurality of grate bar assemblies carried by said beams, each assembly comprising a plurality of spaced apart parallel supporting rods extending transversely of said beams and of a length to extend from the intermediate portion of one beam to the intermediate portion of the adjacent beam, a plurality of parallel grate bars carried by said rods, spacing means on each grate bar cooperating with the said rods for holding said grate bars in parallel spaced apart relationship thereon, the grate bars at the end of the rod resting upon the beams, the grate bars between the beams having a depth greater than that of the bars which rest upon the beams, and the grate bar adjacent each beam abutting the beam to hold the assembly in place. 55

7. A grate bar assembly comprising a plurality of spaced supporting members, a plurality of 70 grate bars arranged in parallel relation with one another and with said supporting members, a plurality of supporting bars having a length substantially equal to the distance between said supporting members extending transversely through said grate bars and above said supporting members to support the grate bars in the spaces intermediate the supporting members, 75

5 said grate bars having portions depending below said transverse supporting bars, the grate bars adjacent the ends of the supporting bars having their depending ends shorter than the other grate bars and being positioned upon the supporting members to support through their depending portions the transverse supporting bars and the grate bars carried by the latter intermediate the supporting members.

10 8. A grate bar assembly comprising a series of spaced supporting members, a plurality of supporting bars lying transverse to the supporting members and bridging the spaces therebetween, a plurality of grate bars arranged in parallel relation with one another and provided with aligned apertures through which extend the

transverse supporting bars, spacer elements on each individual grate bar spacing each grate bar from the other, said grate bars having portions depending below the transverse supporting bars, the grate bars adjacent the ends of the supporting bars having their depending ends shorter than the other grate bars, said supporting members positioned within the recess formed by the shorter grate bars to support the entire grate bar assembly, and the longer depending portion of the grate bars on either side of said recess lying against the side of said supporting members whereby the whole assembly through said spacer elements is compactly held together.
